(57) **CLAIM**

The ornamental design for an input tray for sheet scanner, as shown and described.

DESCRIPTION

FIG. 1 is a front perspective view of an input tray for sheet scanner in accordance with our new design;

FIG. 2 is a rear perspective view thereof;

FIG. 3 is a front elevational view thereof;

FIG. 4 is a rear elevational view thereof;

FIG. 5 is a right-side elevational view thereof;

FIG. 6 is a left-side elevational view thereof;

FIG. 7 is a top plan view thereof;

FIG. 8 is a bottom plan view thereof;

FIG. 9 is a front perspective view of the input tray for sheet scanner of FIG. 1, in which the sheet guides are in an inward position;

FIG. 10 is a front elevation view thereof; and,

FIG. 11 is a top plan view thereof.

Broken lines and unshaded portions contained within broken lines are not claimed.

1 Claim, 11 Drawing Sheets
